UNITED STATES PATENT OFFICE

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA

COKING RETORT OVEN

Application filed February 23, 1923. Serial No. 620,582.

This invention comprehends improvements of general utility in the coking retort oven art; and also comprehends certain improvements especially applicable to coking retort 5 ovens of the well known cross-regenerative type exemplified in the patent to H. Koppers No. 818,033, dated April 17, 1906, and in my prior Letters Patent of the United States No. 1,374,546, for coking retort oven, dated 10 April 12, 1921.

The invention has for objects the provision of a coking retort oven embodying the cross-over oven principle exemplified in my prior patent above mentioned in a "coke oven" employing as fuel its own gas of distillation. 15 Important characteristics of the invention are: a flue construction that permits a considerable reduction not only in the length but also in the cross sectional dimensions of the 20 horizontal or bus flues located at the top of the vertical flame flues and connecting a plurality of the latter with each other; and, as a feature that may be secured by the above structural improvements, a novel system of 25 control of the flow through the flame flues of the heating walls, permitting flow in the same direction through all the flame flues of each heating wall, with the result that all the flame flues of each heating wall are either simultaneously 30 burning or simultaneously operating as downflow flues for carrying away the waste gases to outflow operating regenerators.

With regard to the novel flue construction, for example, a plurality of horizontal flues 35 in each heating wall may be substituted for the usual single horizontal flue which extends from end to end of the heating wall. With a number of separate horizontal flues, each horizontal flue need communicate with only 40 part, in the present instance about one-fifth of the total number of flues of the heating wall and consequently the dimensions of each flue may be considerably decreased because 45 of the consequent reduction in the volume of flow which must be maintained through the horizontal flue. The above stated reduction in size of the horizontal flues is an important advantage for the reason that it enables a considerable thickening and strengthening of 50 the walls of the oven structure in the region

of the horizontal flues. Moreover, the improved flue construction permits an increase in the height of the flame flues, with a corresponding increase in the height of the coking chambers so that the latter may be made 55 narrower in width, a development greatly facilitating the coking of high volatile coals, and yet having adequate provision for taking care of the increased volume of combustion products, without making it necessary to enlarge the horizontal flue dimensions to sizes 60 inconsistent with adequate strength of the wall construction in the region of such flues.

In addition to the objects recited above, the invention has for other objects such other 65 improvements or advantages in construction and operation as are found to obtain in the structures and devices hereinafter described or claimed.

In the accompanying drawings, forming a 70 part of this specification, and showing for purposes of exemplification, a preferred form and manner in which the invention may be embodied and practised, but without limiting the claimed invention to such illustrative instance or instances:

Figure 1 is a crosswise vertical section 75 through a coke oven battery embodying features above specified and equipped with the improvements of the present invention, the view being taken longitudinally through a heating wall and a pair of regenerators, in planes indicated by the lines A—A and B—B of Fig. 2;

Fig. 2 is a composite vertical sectional elevation taken longitudinally of a coke oven 80 battery, in planes indicated by the lines D—D and E—E of Fig. 1; and

Fig. 3 is a vertical sectional view taken transversely of a coke oven battery and 85 through a coking chamber in a plane indicated by the line C—C of Fig. 2.

The same characters of reference indicate the same parts throughout the several views.

Referring to the drawings, there are illustrated views of a coke oven battery or plant of the by-product type, having features above specified; said oven battery embodies in its construction a plurality of crosswise elongated heating walls 11, 11 and a plurality of 100

intermediate crosswise elongated vertical coking chambers 12, 12. The heating walls 11 form the side walls of the respective coking chamber 12, as shown more particularly in Fig. 2. In the present instance the coking chambers 12 are directly supported by the heavy supporting or pillar walls 13, 13 which extend crosswise of the battery and are located respectively, as shown in Fig. 2, beneath the coking chambers. These pillar walls collectively form the main support for the entire super-structure of the oven battery and are themselves supported upon a flat mat or platform which constitutes the sub-foundation on which the entire battery rests. The coal to be coked is charged into the several coking chambers or ovens through charging holes 14 located in the top 15 of the oven battery and positioned directly above the oven or chambers 12, as shown in Figs. 1 and 2. These charging holes 14 are equipped with the usual removable covers, which are removed during charging of the individual ovens or coking chambers and are placed in position to close the tops of such coking chambers during the entire coking or distilling operation. The gases of distillation pass from the tops of the several coking chambers 12 through gas outlets 16 and thence through ascension pipes (not shown) into the usual gas collecting main which carries the distillation products to the by-product recovery apparatus.

Heat for coking the charges of coal in the several ovens or chambers 12 is derived from the heating walls 11, which, as above mentioned, extend crosswise of the battery at the sides of the coking chambers. Referring now more particularly to Figs. 1 and 2, each heating wall 11 is constituted of a plurality of flame or combustion flues 17. The flame flues of each heating wall may be, in accordance with the invention, arranged for flow of the heating gases with all of the flues of each heating wall operating concurrently as upflow or downflow flues, as will be herein-after more fully explained. When the flame flues on one side of a coking chamber are burning, that is to say, operating for upflow, the flame flues on the opposite side of the same coking chamber are operating for downflow to permit exhaust of the waste gases. Consequently heating is maintained continuously from end to end on one side of a charge of coking coal in each coking chamber, the heat being applied to the full length of one side of such charge during an entire period and, then, after reversal being applied to the full length of the opposite side 60 of the charge, until a subsequent reversal is effected.

The crosswise regenerators 18 of the retort oven or battery are located at a lower level than the aforesaid heating walls 11 and coking chambers 12, and, in the present instance,

extend in parallelism between the pillar walls 13. Located in the middle lengthwise vertical plane of the coke oven battery, is a vertical partition 19, as shown in Fig. 1, which partition extends all the way up from the mat of the battery to the bottom of the overlying coking chamber and from one to the other of the pillar walls 13. The regenerators, which are respectively located on opposite sides of the battery extend inwardly to said partition 19 and are separated thereby as clearly shown in Fig. 1. This arrangement permits control from opposite sides of the battery of the flow through the regenerators, thereby assisting the novel flue arrangement in promoting uniformity of distribution. Each regenerator 18 is a chamber containing open brick work, commonly called checker work, and indicated at 20, with a distributing sole channel 21 underneath such checker work, the channels forming the soles of such chambers and opening up into the checker work.

The regenerators are heated, in alternation, by the hot combustion products that draw off from the flame or combustion flues hereinbefore mentioned and then impart such heat to the medium that they feed into these flame flues; in the present instance, the flow through the alternate series of regenerators G is maintained concurrently in the same direction, whereas the flow through the series of intermediate regenerators H is in the opposite direction, for example, when the flow is passing up through the air regenerators G, downflow is being maintained concurrently through the intermediate waste heat regenerators H. Each regenerator is provided with a series of ducts 23 all of which lead respectively to individual flame flues 17 of the same heating wall, so that each heating wall has its own pair of end-to-end positioned regenerators, which function as unit for the up or down flow of the heating gases, in respect of such heating wall.

In the present embodiment of the invention, the entire series of flame flues 17 of each heating wall 11 is either burning or operating for downflow to convey waste products to the regenerators beneath and consequently the regenerators aligned on opposite sides of the central longitudinal partition 19 operate concurrently for flow in the same direction and in the same manner. The reversal in flow through the flame flues 17 on opposite sides of a coking chamber, and their communicably connected regenerators may thus be said to take place longitudinally of the oven battery, instead of transversely thereof, as has heretofore been a common practice in this art. The reversal of the oven is effected at the end of an operating period determined by practice, and by means of any preferred type of reversing mechanism. The function of such reversal is as follows: The alternate regenerators G that prior to the reversal op-

erated as inflow air regenerators become outflow waste heat regenerators, and the intermediate outflow operating regenerators H become inflow operating air regenerators; 5 the upburning series of flue switches function with the downburning series of flues of the next adjacent heating wall, and the supply of gas is turned off from the previously upburning flues and turned on into the mains 10 of the previously downburning flues.

Each flame flue 17 of each heating wall has at its top a port or opening 24 for draft and the passage of combustion products or waste gas from the flame within the flue. These 15 ports 24 open up into horizontal or bus flues 25 formed in the heating walls and connecting all of the vertical flues that communicate with such horizontal flues 25 by means of the ports 24. According to the invention, there 20 are in each heating wall a plurality of, in the present instance five, of such horizontal flues 25 positioned end to end with respect to each other. By reason of the fact that there is a plurality of such horizontal flues 25, these 25 flues 25 are not required to be of so great capacity as that necessary in present practice and consequently the cross-sectional area of each horizontal flue 25 may be materially reduced proportionately with the length of 30 such flue, with the result that the thickness and strength of the heating walls are substantially increased in the region of the horizontal flues. Moreover, because of the fact that each horizontal flue 25 communicates with a 35 substantially reduced number of vertical flues, in the present instance approximately one-fifth of the flues of a heating wall, uniformity in distribution of the flow through the vertical flues and the communicating re- 40 generators is greatly promoted.

As shown, the respective horizontal flues 25 of each heating wall are communicably connected individually by means of cross-connecting passageways or ducts 26 respectively with the corresponding horizontal flues of one of the next adjacent heating walls. These channels 26 preferably open up into substantially the middle portions of their respective connected flues 25, as shown in Fig. 3, and extend longitudinally of the oven battery, as shown in Fig. 2. Thus the entire flow from a heating wall, within the flues of which combustion is being maintained passes through and downwardly through all of the 50 flues of the next adjacent heating wall and each reversal operation is accompanied by a reversal in direction inflow of all of the flues of each heating wall.

Extending crosswise of the battery in each pillar wall 13 and located beneath the heating wall 11 thereabove, is a pair of gas-supply channels 29 and 30. These channels 29 and 30 are for the purpose of supplying coke oven gas to the several flame flues on each side 55 of the central line L, and to accomplish this

end, the channel 29 communicates with the individual flues 17 on the near side of said line L by means of ducts 31 that lead from such channel 29 individually into the bottoms of individual flues; and the channel 30 which supplies the several flues that are located on the far side of the aforementioned dividing line L communicates therewith by means of similarly connecting ducts. Within the several ducts are disposed the usual nozzles 32. 70 The supply of coke oven gas to the respective channels 29 and 30 is derived from the coke oven gas main of the usual type and respectively located on the opposite sides of the battery and extending longitudinally therewith. Suitable means is provided for admitting or cutting off the supply of gas with respect to each pair of channels 29 and 30, it being understood that the gas supply is either concurrently maintained or concurrently shut off from both channels of each pair. 80

The invention as hereinabove set forth is embodied in a particular form of construction but may be variously embodied within the 90 scope of the claims hereinafter made.

I claim:

1. In a coke oven battery, in combination: a series of alternate parallel horizontally elongated coking chambers and heating walls, 95 said heating walls respectively comprising vertical combustion flues; a plurality of horizontal flues in each half of each heating wall and respectively connecting a plurality of the combustion flues of their respective heating walls; each of the horizontal flues being also communicably connected with one of the horizontal flues of an adjacent heating wall; a plurality of pairs of end to end individually 100 regulable and reversible cross-wise extending regenerators adjacent the coking chambers and the heating walls, there being only a pair of the end-to-end positioned regenerators directly connected with the combustion flues of a single heating wall, whereby the alternate 105 regenerators of the battery may be operated for flow in one direction while the intermediate regenerators are operated for flow in the opposite direction; substantially as specified. 110

2. In a coke oven battery, in combination: a series of alternate parallel horizontally elongated coking chambers and heating walls, 115 said heating walls respectively comprising vertical combustion flues; a plurality of horizontal flues in each half of each heating wall and respectively connecting a plurality of the combustion flues of their respective heating walls; each of the horizontal flues being also communicably connected with one of the horizontal flues of an adjacent heating wall; a plurality 120 of groups of end to end individually regulable and reversible crosswise-extending regenerators adjacent the coking chambers and the heating walls, there being only a group of the end-to-end positioned regenerators con- 125

- 5 nected with the combustion flues of a single heating wall, the regenerators connected to the respective walls lying in single file and alternating with those of adjacent walls; substantially as specified.
- 6 3. A coke oven comprising a heating wall having a series of combustion flues therein, a regenerator communicably connected to each of said flues by a group of ducts leading from 10 said regenerator and converging into a single opening leading into the flue; substantially as specified.
- 7 4. In a coking retort oven battery, in combination: a series of alternate substantially 15 parallel horizontal coking chambers and heating walls therefor arranged laterally of each other in a row, each of said heating walls comprising vertical combustion flues; horizontal flow duct means in each of the heating walls and respectively communicably connected with the upper ends of a plurality of the vertical flues of their respective heating walls; the horizontal flow duct means of a heating wall on one side of one of said coking 20 chambers being also communicably connected for passage of combustion products with the horizontal flow duct means of one of the heating walls on the opposite side of said one of said coking chambers by cross-over duct 25 means crossing over the coking chamber; cross-wise regenerators, below the coking chambers and heating walls, said regenerators being individual to said heating walls respectively, and being communicably connected singly with the combustion flues thereof and being at least as wide as the flues with which they communicate; and means for conveying unpreheated fuel gas to each of said vertical combustion flues for combustion therein.
- 8 5. In a coking retort oven battery, in combination: a series of alternate substantially 30 parallel horizontal coking chambers and heating walls therefor arranged laterally of each other in a row, each of said heating walls comprising vertical combustion flues; horizontal flow duct means in each of the heating walls and respectively communicably connected with the upper ends of a plurality of the vertical flues of their respective heating walls; the horizontal flow duct means of a heating wall on one side of one of said coking chambers being also communicably connected for passage of combustion products with the horizontal flow duct means of one of the heating walls on the opposite side of said one of said coking chambers by cross-over duct 35 means crossing over the coking chamber; cross-wise regenerators, below the coking chambers and heating walls, said regenerators being individual to said heating walls respectively, and being communicably connected singly with the combustion flues thereof and being at least as wide as the flues with which they communicate; and means for conveying unpreheated fuel gas to each of said vertical combustion flues for combustion therein.
- 9 6. In a coking retort oven, in combination: a series of alternate substantially parallel horizontal coking chambers and heating walls therefor arranged laterally of each other in a row, each of said heating walls comprising vertical combustion flues; horizontal flow duct means in each of the heating walls and respectively communicably connected with the upper ends of a plurality of the vertical flues of their respective heating walls; the horizontal flow duct means of a heating wall on one side of one of said coking chambers being also communicably connected for passage of combustion products with the horizontal flow duct means of one of the heating walls on the opposite side of said one of said coking chambers by cross-over duct means crossing over the coking chamber; and individual regenerators arranged side-by-side in a row longitudinally of the oven below the coking chambers and heating walls and communicably connected with the combustion flues of said heating walls; said regenerators being each at least as wide as the vertical flues and being each communicably connected with each flue in communication therewith by a group of ducts leading from 100 each of the heating walls on the opposite side of said one of said coking chambers by cross-over duct means crossing over the coking chamber; and individual regenerators arranged side-by-side in a row longitudinally of the oven below the coking chambers and heating walls and communicably connected with the combustion flues of said heating walls; said regenerators being each at least as wide as the vertical flues and being each communicably connected with each flue in communication therewith by a group of ducts leading from 105 each of the heating walls on the opposite side of said one of said coking chambers by cross-over duct means crossing over the coking chamber; and individual regenerators arranged side-by-side in a row longitudinally of the oven below the coking chambers and heating walls and communicably connected with the combustion flues of said heating walls; said regenerators being each at least as wide as the vertical flues and being each communicably connected with each flue in communication therewith by a group of ducts leading from 110 each of the heating walls on the opposite side of said one of said coking chambers by cross-over duct means crossing over the coking chamber; and individual regenerators arranged side-by-side in a row longitudinally of the oven below the coking chambers and heating walls, said regenerators being operatively disposed in two series operable in alternation with each other for upflow and downflow with the vertical flues of one series communicably connected at their upper parts with the vertical flues of the other series at their upper parts for simultaneous reverse flow of gas from one to the other in alternation; and individual regenerators arranged side-by-side in a row longitudinally of the oven below the coking chamber and heating walls, said regenerators being operatively disposed in two series operable in alternation with each other for inflow and outflow; the regenerators of one of said two series thereof being communicably connected with vertical flues of one of said two series thereof, and the regenerators of the other series of said two series thereof being communicably connected with the vertical flues of the other series of said two series thereof; the regenerators of said two series being each at least as wide as the vertical flues and being each communicably connected with each flue in communication therewith by a group of ducts leading from 115 each of the heating walls on the opposite side of said one of said coking chambers by cross-over duct means crossing over the coking chamber; and individual regenerators arranged side-by-side in a row longitudinally of the oven below the coking chambers and heating walls, said regenerators being operatively disposed in two series operable in alternation with each other for inflow and outflow; the regenerators of one of said two series thereof being communicably connected with vertical flues of one of said two series thereof, and the regenerators of the other series of said two series thereof being communicably connected with the vertical flues of the other series of said two series thereof; the regenerators of said two series being each at least as wide as the vertical flues and being each communicably connected with each flue in communication therewith by a group of ducts leading from 120 each of the heating walls on the opposite side of said one of said coking chambers by cross-over duct means crossing over the coking chamber; and individual regenerators arranged side-by-side in a row longitudinally of the oven below the coking chambers and heating walls, said regenerators being operatively disposed in two series operable in alternation with each other for inflow and outflow; the regenerators of one of said two series thereof being communicably connected with vertical flues of one of said two series thereof, and the regenerators of the other series of said two series thereof being communicably connected with the vertical flues of the other series of said two series thereof; the regenerators of said two series being each at least as wide as the vertical flues and being each communicably connected with each flue in communication therewith by a group of ducts leading from 125 each of the heating walls on the opposite side of said one of said coking chambers by cross-over duct means crossing over the coking chamber; and individual regenerators arranged side-by-side in a row longitudinally of the oven below the coking chambers and heating walls, said regenerators being operatively disposed in two series operable in alternation with each other for inflow and outflow; the regenerators of one of said two series thereof being communicably connected with vertical flues of one of said two series thereof, and the regenerators of the other series of said two series thereof being communicably connected with the vertical flues of the other series of said two series thereof; the regenerators of said two series being each at least as wide as the vertical flues and being each communicably connected with each flue in communication therewith by a group of ducts leading from 130

two opposite sides thereof to the respective flues in communication therewith.

8. In a coking retort oven, in combination: a series of alternate substantially parallel horizontal coking chambers and heating walls 5 therefor arranged side-by-side, each of said heating walls comprising vertical combustion flues; horizontal flow duct means in each of the heating walls and respectively communicably connected with the upper ends of a plurality 10 of vertical flues of their respective heating walls; the horizontal flow duct means of a heating wall on one side of one of said coking chambers being also communicably connected for passage of combustion products with the 15 horizontal flow duct means of one of the heating walls on the opposite side of said one of said coking chambers by cross-over duct means crossing over the coking chamber; vertical pillar walls directly beneath, and extending 20 up to the bottom of, the coking chambers and parallel therewith, said pillar walls being the only vertical walls that are parallel with said coking chambers and heating walls and directly below the coking chambers and heating 25 walls and forming a support for the heating walls and coking chambers; regenerators located directly beneath the heating walls and between the pillar walls and communicating 30 with the flues of the heating walls; and gas conduits located within the bottoms of each of said heating walls and extending lengthwise thereof and communicably connected with a plurality of the vertical flues of their respective heating walls for supplying thereto unpreheated combustible gas thereto. 35

9. In a coking retort oven, in combination: a series of alternate substantially parallel horizontal coking chambers and heating walls 40 therefor arranged side by side; each of said heating walls comprising vertical combustion flues operable in alternation for upflow and downflow; vertical pillar walls directly beneath, and extending up to the bottoms of, the 45 coking chambers and parallel therewith, said pillar walls being the only vertical walls that are parallel with said coking chambers and heating walls and directly below the coking chambers and heating walls and forming a support for the heating walls and coking 50 chambers; regenerators located directly beneath the heating walls and between the pillar walls and communicating with the flues of the heating walls; and gas-conveying channels located within the bottoms of each of said heating 55 walls and extending lengthwise thereof and communicably connected with the vertical flues of their respective heating walls for supplying thereto unpreheated fuel gas for combustion therein.

In testimony whereof I have hereunto set my hand.

JOSEPH BECKER.
